UNITED STATES PATENT OFFICE.

WILLIAM A. CHRYSST, OF DAYTON, OHIO, ASSIGNOR TO THE DAYTON ENGINEERING LABORATORIES COMPANY, A CORPORATION OF OHIO.

ENGINE-STARTING SYSTEM.

1,386,316.

Specification of Letters Patent.

Patented Aug. 2, 1921.

Application filed September 5, 1916. Serial No. 118,458.

To all whom it may concern:

Be it known that I, WILLIAM A. CHRYSST, a citizen of the United States of America, residing at Dayton, county of Montgomery, 5 and State of Ohio, have invented certain new and useful Improvements in Engine-Starting Systems, of which the following is a full, clear, and exact description.

The present invention relates to an improvement in starting systems for engines, and more particularly to systems of this type, wherein the starting device is adapted to be coupled to the engine for starting purposes, and the engine, when once started, is 15 adapted to be coupled to the starting device to actuate the same to store up power for future starting operations and for other purposes.

One of the objects of the present invention 20 is to provide a supplemental system for engines of the non-self starting type, including a power actuated prime mover, normally disconnectible from the engine, but having connecting devices automatically operable 25 for effecting the coupling up of the electric machine and engine together, in combination with controlling mechanism, whereby the various functions of the system, and certain 30 functions of the engine may be automatically controlled by an initial operation of the electrical system.

That is, in one form of embodiment of the present invention, this starting system may include an electric machine, capable of operation either as a motor or as a generator, in combination with connecting devices, which are normally in uncoupling position, but which may be automatically and positively shifted into one position to couple up the 35 engine and the electric machine for starting purposes, and then when the engine has been started, these connecting devices may be automatically shifted to a different position to couple up the electric machine and the 40 engine, whereby said electric machine may drive the engine as a generator. These connecting devices are so constructed and arranged that when the electric machine is being operated as a motor for starting purposes, it will crank the engine at one ratio 45 of speed, while when the engine is connected to the electric machine through other combinations of the connecting devices, the engine and the electric machine will operate 50 at a different speed ratio.

In the embodiment of the present invention, wherein these connecting devices include gearing, which is shiftable to enmeshed and unmeshed positions, the automatic shifting of the connecting devices will preferably 60 accompany an initial motor movement of the electric machine, so as to facilitate the enmeshing operation of the gearing. This same shifting of the connecting devices, which may be said to be controlled by the 65 initial motor movement of the electric machine, may control the closing of certain circuit connections, whereby the electric machine will be brought into operation as a motor for actual starting purposes. 70

This latter operation may also be so controlled that it will not take place until the connecting devices have been shifted to a determined coupling position. That is, the 75 operation of the electric machine as a motor for starting purposes, will not take place until the proper enmeshment of the gearing has taken place.

This same automatic shifting of the connecting devices may also effect the discontinuation of the initial motor movement of the machine, substantially concomitantly with the proper unmeshment of the mechanical connections and the establishment of the 80 electrical connections for causing the machine to operate as a motor for starting purposes. 85

Further objects and advantages of the present invention will be apparent from the following description, reference being had 90 to the accompanying drawings, wherein a preferred form of the present invention is clearly set forth:

In the drawings:—

Figure 1 is a view of an automobile chassis, 95 wherein the different units of the present invention and the electrical connections are diagrammatically shown.

Fig. 1^A is a wiring diagram of the electrical circuits included in the present invention. 100

Fig. 2 is a view partly in section of the starting device, showing the relative positions of the shiftable connections when the electric machine is being driven by the engine. 105

Fig. 3 is a view similar to the Fig. 2, showing the shiftable connections in position for the cranking operation.

Referring to the drawings and more par- 110

ticularly to Figs. 1, 2 and 3, it will be noted that the numeral 20 designates the engine, which is shown in the present instance as being embodied in a motor vehicle, and 5 which constitutes the power plant therefor. The vehicle in the present instance is designated by the numeral 21, and comprises a pair of side frames 22, between which the engine 20 is mounted on any suitable structure 10 of cross members. The engine 20 may be of any approved multiple cylinder type.

The numeral 23 designates an electric machine which has the dual characteristics of a motor and of a generator. This machine 15 is mounted on the vehicle frame or some part of the engine, in such a manner that the driving end thereof is in position to be connected to some moving part of the engine, such as for instance, the crank shaft 20 thereof, or some shaft having driving connection with said crank shaft.

In the form of the invention shown in the accompanying drawings, the electric machine is illustrated as being connected by 25 means of a belt or chain or other flexible connection 25, with the crank shaft 26 of said engine.

The electric machine 23 includes an armature 23^a a shunt field 23^b and a high torque 30 field 23^c. Armature 23^a is mounted upon a shaft 28, which projects outwardly from the casing 29 of the electric machine, and carries a pinion 30, which is made fast to said shaft in any suitable manner. The shaft 28 is provided 35 with depressions or notches 32, which are shallow at the end nearest said pinion, but are gradually increased in depth.

A ring gear 33 is mounted upon the armature shaft 28 and includes a clutch structure comprising a shell 34, wherein are carried suitable pawls 35, which as will be described hereinafter, engage with the notches 32 under certain conditions to effect a direct driving relation between the ring gear and 45 the armature shaft.

This ring gear also has a pair of arms 36 secured thereto, which are connected with a grooved collar 37 internally threaded to engage with the threaded shaft 38, (see Figs. 50 2 and 3). The shaft 38, which may be referred to as a screw threaded shaft, is connected with a pulley or sprocket member 39, over which a belt connection 25 passes. Any suitable supporting member 40 may be 55 combined with the structure heretofore described, for maintaining the alinement and also acting as a bearing for the threaded shaft 38 and the pulley or transmission member 39.

60 Adjacent to the armature shaft 28, and in parallel relation thereto, a stub shaft 41 is secured to the casing of the electric machine, or to any other suitable support, and is adapted to carry a large pinion 43, and a small 65 pinion 44, which are preferably mounted

upon a sleeve 45, which in turn is slidably mounted on the shaft 41. This sleeve also is provided with the grooved collar 46, to receive the pins 47, carried by the pitman 48, one end of which is connected to the 70 sleeve 45, by the pins 47, while the other end of said pitman is connected to the ring gear assembly 33, by the pins 49, which engage with the grooved collar 37.

From the above description, it will be seen 75 that the operation of the device will be as follows:

Supposing that the engine is at rest and it is desired to start the same. The operator simply has a single operation to perform, in order, first, to couple up the electric machine and the engine and, concomitantly with this coupling up operation, to impart an initial movement to the electric machine and to the intermediate connecting devices 80 so as to facilitate the coupling up of the electric machine and the engine, and then to effect the actual starting operation of the engine, and finally to change the ratio of 85 the driving connections between the electric machine and the engine whereby the said engine will operate the electric machine as a generator at the proper speed.

By referring to the diagram in Fig. 1^A, it will be noted that when the operator by 95 pressing button 64 closes the contacts 50, the following circuit will be closed:

From the positive side of the battery 51, across the contacts 50 of the cut-out relay through the relay series coil 62 to the ground 100 52, thence to the corresponding ground 53, through armature 23^a and shunt field 23^b of the electrical machine 23 and back to the opposite side of the battery via the wire 54.

As soon as the above mentioned circuit is 105 closed, the electric machine will begin to operate as a motor, but due to the relatively high resistance of the circuit connections referred to above, the speed and torque effect of this motor movement will be relatively small.

Now, concomitantly with this initial movement of the electric machine as a motor, the armature shaft will of course start to revolve, and this in turn will revolve the pinions 30 and the ring gear 33, through the pawl clutch heretofore described, inasmuch as the pawls in their normal position are seated in the deepest part of the slots or notches 32.

115 As a consequence of the rotation of the ring gear 33, the collar 37 will rotate, and inasmuch as this collar is internally threaded, the ring gear and the pawl members of the clutch, together with the collar 37, will move 120 in the direction of the arrow shown in Fig. 2.

Concomitantly with this movement of the ring gear 33, the pitman 48 will be actuated to effect a shifting of the pinions 43 and 44 in an opposite direction to that of the ring 125 130

gear 33, these pinions 43 and 44 moving in the direction of the arrow B—B shown in Fig. 2.

This movement of the above mentioned parts will continue as the pinion 43 is brought into enmeshment with the pinion 30; and, inasmuch as the pinion 30 is already rotating, the enmeshment of these two parts will readily ensue, since any tendency for conflict of the end faces of the teeth of these two members will be reduced to a minimum by the relative rotation of the member 30. Of course, a rotary movement will then be imparted to the pinions 43 and 44, so that the pinion 44 will readily enmesh with the ring gear 33, as soon as these parts have been moved to enmeshed position.

During the movement of the ring gear 33, and its associated parts, as described above, it will be noted that the pawl members 35 are riding on the faces of the notches 32, and inasmuch as these faces are inclined, it will be seen that as soon as the pinion 44 and the gear 33 tend to enter enmeshment, and are slightly enmeshed, these pawls will readily disengage from their clutching effect with the shaft 28, so that the ring gear 33 will rotate relative to the pinion 30 and the armature shaft 28. This disengaging of the pawls 35 at the time pinion 44 and gear 33 are slightly enmeshed is possible since said pawls will then be located in the shallower portions of the notches 32 and can more readily give way to the driving of gear 33 by pinion 44.

Now, as soon as both sets of enmeshing gearing are brought into fully enmeshed position, it is desirable to transmit a high torque and relatively high speed effect of the armature through this set of reduction gearing to the threaded shaft 38. Inasmuch as the collar 37 has moved into position to engage with the abutment 51 carried by the shaft 38, a positive drive will be effected from the armature shaft directly to the transmission member 39 and thence to the crankshaft of the engine through the connection 25.

This high torque effect is obtained by closing an electric circuit through the separate field 23^c in the motor-generator, by means of the pitman 48 and the contacts 57. When the pitman 48 is in the position shown in Fig. 3, the contacts are closed, completing the circuit through the high torque windings 23^c of the motor-generator as follows: from the battery 51, through the lead 58, thence across the contacts 57, through the lead 56, windings 23^c, armature 23^a, and back to the battery via the wire 54.

This high torque movement will continue as long as the main motor circuit is closed or until such time as the engine becomes self-actuating. Upon the engine starting, however, it will be seen that as soon as the en-

gine reaches a normal running speed, the shaft 38 will be rotated by the engine faster than the pinion 33 is rotated by means of the motor drive, due to the difference in dimensions between the respective pinions 30, 43, 44 and 33, so that the internally threaded collar 37 will tend to be screwed back into normal position, thereby drawing the gear 33 and its associated parts in the same direction.

This same operation of the collar 37 will tend to also shift the pitman 48 in such a direction as to throw the pinions 43 and 44 into their normal disengaged position (see Fig. 2).

During the movement of the ring gear 33 to its normal position, the pawls 35 will again engage in the deeper parts of the notches 32 and thereby tend to turn the armature shaft 38. Now, as soon as the collar 37 reaches the position shown in Fig. 2, further longitudinal movement will be arrested. A direct drive from the crank shaft of the engine will then be transmitted to the armature shaft, through the transmission connection 25, pulley 39, screw threaded shaft 37, the ring gear 33 and its clutch connection with the armature shaft 28.

In the meantime, the motor circuit will be disconnected and the generator connections established between the battery and the electric machine, so that as the electric machine is brought into operation as a generator, it may readily charge the batteries at the proper rate.

The reverse current relay operates in the well known manner to maintain the charging circuit closed unless there is a tendency for the battery to discharge through the generator. The usual voltage or holding coil 63 co-operates with the series coil 62 to maintain armature 60 in attracted position toward core 61. Contacts 50 are therefore maintained closed during these conditions.

It will be noted from the foregoing description that by the simple closing of an electric circuit (as by closing the relay contacts 50), the electric machine is first caused to couple itself up to the engine through gearing connections having the proper ratio of speed for engine starting, and then the electric machine is caused to operate with the proper torque to effect engine starting. The engine, having become self-operative, causes first, the changing from these gearing connections used during engine starting to other gearing connections having the proper speed ratio for generating purposes and the disconnection of circuits used during the engine cranking operation, and then the engine drives the electric machine as a generator. It will be noted that no manual effort is required to shift the gearing between the engine and the electric machine, but that this gear shifting is effected in a

positive manner and automatically depending on whether the electric machine or the engine constitutes the driving member.

It will be noted that the present invention provides power transmitting means between the dynamo-electric-machine and the engine, having a single connection with the engine as well as the power transmitting means which includes automatic means for changing the speed ratio of these connections depending on whether the electric machine or the engine becomes the driving member. This feature of the invention is advantageous especially where it is desired to provide an internal-combustion engine with a starting and battery charging system, the engine not having been originally designed and provided with gearing to receive the starting and generating unit.

20 While the form of mechanism herein shown and described, constitutes a preferred form of embodiment of the invention, it is to be understood that other forms might be adopted all coming within the scope of the 25 claims which follow.

What I claim is as follows:

1. In an engine starting system, the combination with an engine; of an electric machine operable as a generator or as a motor; 30 a storage battery; provisions for connecting the machine and engine at different speed ratios; means for causing the machine to operate with an initial low torque movement; an automatic means operating during said 35 low torque movement positively to connect the machine and engine for starting purposes and then to effect the high torque operation of the machine as a motor, said automatic means operating positively to connect the 40 engine and machine for generating purposes when the engine becomes the driving member.

2. In an engine starting system, the combination with an engine; of an electric machine operable as a generator or as a motor; 45 a storage battery; provisions for connecting the machine and engine at different speed ratios, including means normally connecting the machine and engine for generating purposes, and including shiftable gearing for 50 connecting the machine and engine for starting purposes; means for causing the machine to operate with an initial low torque movement; and automatic means operating during said 55 low torque movement positively to shift said gearing and to disconnect said generating connections, and to effect the high torque operation of the machine as a motor when said gear shifting is substantially completed, said automatic means operating 60 positively to reestablish said generating connections when the engine becomes the driving member.

3. In an engine starting system, the combination with an engine; of an electric ma-

chine operable as a generator or as a motor; a storage battery; provisions for connecting the machine and engine at different speed ratios, including means normally connecting the machine and engine for generating purposes, and including shiftable gearing for connecting the machine and engine for starting purposes; means for causing the machine to operate with an initial low torque movement; means for producing the high torque 70 operation of the machine as a motor, including a high torque winding and a switch for controlling the same; and automatic means operating during said low torque movement positively to shift said gearing and to disconnect said generating connections and to close said switch when the gear shifting is substantially completed, said automatic means operating positively to reestablish said generating connections when the 75 engine becomes the driving member.

4. In an engine starting system, the combination with an engine; of an electric machine operable as a generator or as a motor; a storage battery; provisions for connecting the machine and engine at different speed ratios; means for causing the machine to operate with an initial low torque movement; means for producing the high torque 80 operation of the machine as a motor, including a high torque winding and a switch for controlling the same; and automatic means operating during said low torque movement positively to connect the machine and engine for starting purposes and then to 85 close said switch, said automatic means operating positively to connect the engine and machine for generating purposes when the engine becomes the driving member.

5. In an engine starting system, the combination with an engine; of an electric machine operable as a generator or as a motor; a storage battery; connecting devices between the engine and machine certain of which are normally engaged to connect the machine and engine at one speed ratio for generating purposes, certain of said devices including normally unmeshed pairs of gears; means for connecting the battery and machine so as to impart a low torque 90 initial movement thereto; means automatically operable during said initial movement of said machine for effecting the discontinuance of the generating connection and for effecting the enmeshment of first one pair of gears and then another whereby the machine and engine will be connected at another speed ratio for starting purposes; and switch means automatically operable concomitantly with completion of 95 said gear enmeshment for effecting the high torque motor operation of said machine.

6. In an engine starting system; the combination with an engine; of an electric machine capable of acting as a starting device; 100

- means for imparting motion to the electric machine; change speed gearing between the electric machine and the engine capable of rearrangement to effect a plurality of gearing combinations; and means acting automatically upon the operation of the electric machine as a motor positively to effect a gearing connection of a certain combination between the motor and engine, said automatic means being capable when the engine becomes self-actuating of rearranging the change-speed gearing whereby a different gearing combination is effected when the engine drives the machine as a generator.
7. In an engine starting system, the combination with an engine; of an electric machine operable as a motor or as a generator; a storage battery; change-speed gearing devices between the electric machine and engine normally arranged to effect a connection between the engine and electric machine for driving the machine by the engine for generating purposes at a certain speed relatively to the engine; means for effecting electrical connections between the battery and electric machine for effecting the engine starting operation; and means operating automatically upon the initial movement of the machine as a motor for positively rearranging the change-speed gearing devices whereby the engine will be connected with the machine by a different combination of gearing for engine starting purpose, said means operating when the engine becomes self-actuating positively to return the change-speed gearing devices to the normal arrangement for generating purposes.
8. In an engine starting system, the combination with an engine; of an electric machine having an armature and operable as a generator or as a motor, said machine having high torque windings capable when energized of producing a strong turning effect on the armature; a storage battery; change-speed gearing devices normally arranged in a certain combination to effect a connection between the engine and machine for operating the machine as a generator; means for connecting the storage battery with the machine to effect the initial movement of the machine; and means acting automatically upon said initial movement for positively rearranging the gearing between the engine and machine and at the same time to bring the high torque windings of the machine into operation, said automatic means capable, when the engine becomes self-actuating, of positively returning the change-speed gearing to normal arrangement and of rendering the high torque windings inoperative.
9. In an engine starting system, the combination with an engine; of an electric machine operable as a generator or as a motor; a storage battery; devices normally ar-

ranged to connect the machine with a part of the engine at one speed ratio for generating purposes; means for connecting the battery and machine to operate the same as a motor; and means operating automatically during the motor operation of said machine for positively rearranging said devices in order to connect the machine with said engine part at a different speed ratio for engine starting purposes.

10. In an engine starting system, the combination with an engine; of an electric machine operable as a generator or as a motor; a storage battery; means for connecting the machine with an engine part at one speed ratio for generating purposes, or with said engine part at a different speed ratio for engine starting purposes, said means normally providing the generating connection; means for connecting the battery and machine to operate the same as a motor; and means operating automatically during the motor operation of said machine for positively effecting the discontinuance of the generator connection and the establishment of the motor connection.

11. In an engine starting system, the combination with an engine; of an electric machine operable as a generator or as a motor; a storage battery; means for connecting said battery with said machine to operate the same as a motor; devices for connecting the machine with the engine at one speed ratio for generating purposes or at a different speed ratio for engine starting purposes, said devices including speed reduction gearing, a shaft connected with an engine part and provided with spaced stops and external screw threads intermediate said stops, an internally threaded member coöperating with said shaft and normally engaging one of said stops and arranged to effect said generating connection, but capable of longitudinal movement to engage said other stop when said machine operates as a motor, and concomitantly therewith to effect the enmeshment of the speed reduction gearing and the discontinuance of the generating connection.

12. In an engine starting system, the combination with an engine; of an electric machine operable as a generator or as a motor; a storage battery; a gear shifting device operating automatically depending on whether the motor or the engine becomes the driving element, said device including a member having spaced stops and an intermediate screw and a nut mounted on said screw, said screw member being restrained from longitudinal movement but rotatably connected to the engine, and a gear shifting lever coöperating with the nut; means for connecting said nut with the motor shaft including a clutch; speed reduction gearing including a pinion connected to the motor

shaft, a gear connected with said nut, and an axially movable gear and pinion coöperating with said gear shifting lever, and connected together and adapted to mesh, respectively, with the motor shaft pinion and the gear connected to the nut; and means for electrically connecting the motor and battery, said clutch being yieldable when the nut is being driven by the motor through the reduction gearing.

13. In an engine starting system, the combination with an engine; of an electric machine operable as a motor or as a generator; a storage battery; a power transmitting device connected to the engine and including a member automatically shiftable depending on whether the machine or engine constitutes the driving member; a normally operative clutch connecting said machine with said power transmitting device and controlled by said shiftable member; normally inoperative reduction gearing for connecting said machine with said power transmitting device and controlled by said shiftable member; means for connecting the battery and machine, whereby, when the machine operates as a motor, the shiftable member will be caused to render the reduction gearing operative and the clutch inoperative and motion to be transmitted from the motor to the engine, and whereby, when the engine becomes operative, the shiftable member will be caused to render the reduction gearing inoperative and the clutch operative and the machine to be driven by the engine.

14. In an engine starting system, the combination with an engine; of an electric machine operable as a motor or as a generator; a storage battery; provisions connected with the machine and making a single connection with the engine and normally arranged to

connect the machine and engine at one speed ratio for generating purposes, but capable of rearrangement to connect the machine and engine at a different speed ratio for starting purposes, and including automatic means for effecting the starting connection and disestablishing the generating connection when the machine is operated as a motor, and for disestablishing the starting connection and restoring the generating connection when the engine becomes self-operative; and means for connecting the battery with the machine to operate the same as a motor.

15. In an engine starting system, the combination with an engine; of an electric machine operable as a motor or as a generator; a storage battery; provisions connected with the machine and making a single connection with the engine and including a normally operative clutch for transmitting power from the engine to the machine to operate the same as a generator, and including normally disengaged reduction gearing for transmitting power from the machine to the engine for starting purposes, and automatic means for positively rendering the clutch inoperative and for positively engaging said reduction gearing when the machine operates as a motor to start the engine, said automatic means operating when the engine becomes self-operating positively to disengage said gearing and to render the clutch operative; and means for connecting the battery and motor to operate the same as a motor.

In testimony whereof I affix my signature in the presence of two subscribing witnesses.

WILLIAM A. CHRYST.
